(57) **CLAIM**

The ornamental design for an in-ground niche, as shown and described.

DESCRIPTION

FIG. 1 is a perspective view of a single-deep in-ground niche showing my new design;

FIG. 2 is a front elevation view of the single-deep in-ground niche;

FIG. 3 is a rear elevation view of the single-deep in-ground niche;

FIG. 4 is a right side elevation view of the single-deep in-ground niche, the left side being a mirror image;

FIG. 5 is a top plan view of the single-deep in-ground niche;

FIG. 6 is a bottom plan view of the single-deep in-ground niche;

FIG. 7 is a perspective view of a double-deep in-ground niche showing my new design;

FIG. 8 is a front elevation view of the double-deep in-ground niche;

FIG. 9 is a rear elevation view of the double-deep in-ground niche;

FIG. 10 is a right side elevation view of the double-deep in-ground niche, the left side being a mirror image;

FIG. 11 is a top plan view of the double-deep in-ground niche; and,

FIG. 12 is a bottom plan view of the double-deep in-ground niche.
